UNITED STATES PATENT OFFICE.

JOEŽEP KOGOLSHSEK, OF KLEIN, MONTANA.

BLASTING-CARTRIDGE.

1,358,318.

Specification of Letters Patent. Patented Nov. 9, 1920.

Application filed July 7, 1920. Serial No. 394,443.

To all whom it may concern:

Be it known that I, JOEŽEP KOGOLSHSEK, a citizen of Jugo-Slavia, residing at Klein, in the county of Musselshell and State of 5 Montana, have invented certain new and useful Improvements in Blasting-Cartridges, of which the following is a specification.

This invention relates to certain new and useful improvements in blasting cartridges 10 particularly serviceable in shooting down coal in mines although capable of service generally wherever blasting is carried on.

The primary object of the present invention is to provide a blasting cartridge of 15 the above kind which is extremely simple and durable in construction as well as efficient in operation and capable of being manufactured at a very low cost.

Another object of the invention is to provide a blasting cartridge constructed for 20 ignition by a characteristic form of sparking means whereby the use of objectionable fuses or squibs is avoided.

With the above and other objects in view, 25 the present invention consists in the novel form, combination and arrangement of parts hereinafter more fully described and shown in the accompanying drawing, wherein like reference characters indicate similar parts 30 throughout the several views.

In the drawing,

Figure 1 is a substantially central longitudinal sectional view of a cartridge constructed in accordance with the present invention and shown operatively associated 35 with a shot hole and a tamping rod prior to its ignition,

Fig. 2 is an enlarged view of the cartridge partly in longitudinal section and partly in 40 elevation,

Fig. 3 is a transverse sectional view thereof taken upon line III—III of Fig. 1 and drawn on a larger scale,

Fig. 4 is a view of one end of the tamping 45 rod which is preferably employed for folding the casing of the cartridge and

Fig. 5 is a perspective view of one of the sparking terminals.

Referring more in detail to the several 50 views, the present cartridge is adapted to be placed in the usual manner within a shot hole 5 and embodies a tubular casing 6 constructed of any desired insulating or insulated material and closed at its inner end by 55 a suitable plug or stopper 7, the other end of the tube being open so as to have the

powder introduced therein as at 8 and then to receive the packing or stopper 9 in its outer end in the form of waste or the like. The packing 9 and explosive powder 8 is 60 tamped tightly in the casing 6 by any suitable form of tamper, but the preferred form of tamper is shown in the drawing as including a handle or staff 10 having a tamper disk 11 detachably fastened on one end 65 thereof by means of a spring catch 12 carried by the handle 10 and projecting through a sleeve 13 rigid with the disk 11 and into a suitable socket of the handle. This form of tamping rod will give best re- 70 sults and the disk 11 may be removed for being replaced by a larger or smaller one in accordance with the size of fuse being used.

A pair of relatively long sparking terminals 14 are disposed against the opposite sides of and within the casing 6 longitudinally of the latter, and these sparking terminals have angularly bent inner ends 15 which are directed toward each other in 75 slightly spaced relation so as to provide a spark gap therebetween. The outer ends of the terminals 14 are formed each with a pair of loops 16 and 17, one upon the extreme end portion of the terminal and the 80 other slightly inwardly from the end, the former loop being adapted for connection with an electric wire 18 and the other loop of each terminal being bolted as at 19 be- 85 tween a pair of ears 20 rigid with and pro- jecting from the adjacent end of the casing 6. It is to be understood that the wire 18 is connected to one terminal while another wire 21 is connected to the other sparking 90 terminal, the wire 18 being extended to a 95 suitable distant point and attached to one contact 22 of a switch 23 whose other contact is connected with a battery 24 at one side. The other side of the battery is connected to the wire 21. 100

In operation, the casing 6 is placed in the shot hole 5 and a suitable quantity of powder 8 is tamped into the casing about to the section line III—III of Fig. 1, and then the two sparking terminals 14 are placed in the 105 casing and secured in their respective positions by bolting as at 19. A little more powder is then tamped into the casing and this is followed up by tamping the packing 9 in the latter whereupon the cartridge is 110 ready for use. The switch 23 is closed so as to allow the current to flow from the

battery through the wire 18 and one sparking terminal 14 across the gap between the terminal ends 15 and then back through the other sparking terminal and wire 21 to the 5 battery. Upon the production of a spark between the ends 15 of the terminals, the powder 8 is ignited and the cartridge is caused to explode for shooting down the material being blasted.

- 10 From the foregoing description, it is believed that the construction and operation as well as the advantages of the present invention will be readily understood and appreciated by those skilled in the art.
- 15 Minor changes may be made without departing from the spirit and scope of the invention as hereinafter claimed.

What is claimed as new is:

A blasting fuse including a tubular casing closed at one end and having an explosive powder and a packing tamped therein so that the packing forms a plug for the other end of the casing, means including a pair of sparking terminals arranged longitudinally within the casing for igniting said 25 explosive powder, each of said sparking terminals having a loop formed therein adjacent its outer end, pairs of ears rigid with the outer end of the casing, each pair of ears having one of said sparking terminal loops arranged therebetween, and means to bolt said terminals to said ears.

In testimony whereof I affix my signature.

JOEŽEP KOGOLŠHSEK.
